(57) **CLAIM**

(21) Appl. No.: **29/129,393**

We claim the ornamental design for building structure for combined self-serve car wash and automatic car wash, as shown and described.

(22) Filed: **Sep. 13, 2000**

DESCRIPTION

(51) LOC (7) Cl. **25-03**

FIG. 1 is front elevational view of a building structure for combined self-serve car wash and automatic car wash showing our new design, with the automatic door closed;
FIG. 2 is a front elevational view thereof, with the automatic door opened;

(52) U.S. Cl. **D25/34**

FIG. 3 is a rear elevational view thereof, with the automatic door closed;
FIG. 4 is a rear elevational view thereof, with the automatic door opened;

(58) Field of Search D25/1, 4, 22, 33,

FIG. 5 is a left side elevational view thereof;
FIG. 6 is a right side elevational view thereof;

D25/34, 29; 52/79.1, 79.4, 79.9, DIG. 17;
134/123, 45; 15/DIG. 2; D32/4

FIG. 7 is a top plan view thereof; and,
FIG. 8 is an enlarged partial left side perspective view
